CLAIM

The ornamental design for a strip of plastic fastening clips for the fastening of electrical wires, tubes and the like, as shown and described.

DESCRIPTION

FIG. 1 is a perspective view of another strip of separable plastic clips for the fastening of electrical wires, tubes and the like;

FIG. 2 is a bottom view of the strip of FIG. 1;

FIG. 3 is a side view of an individual separately for clarity of illustration; and,

FIG. 4 is a front view of the separated clip of FIG. 3.
